UNITED STATES PATENT OFFICE.

EDWARD GALE MARTIN, OF TYLER, TEXAS, ASSIGNOR OF TWO-THIRDS TO JOSEPH SHERMAN MILLER, OF TYLER, TEXAS, AND WILLIAM NEWTON HURT, OF SHAWNEE, OKLAHOMA TERRITORY.

SPRING-SUPPORT FOR VEHICLE-TOPS.

SPECIFICATION forming part of Letters Patent No. 761,239, dated May 31, 1904.

Application filed December 22, 1902. Serial No. 136,217. (No model.)

To all whom it may concern:

Be it known that I, EDWARD GALE MARTIN, a citizen of the United States, residing at Tyler, in the county of Smith and State of Texas, have 5 invented new and useful Improvements in Spring-Supports for Vehicle-Tops, of which the following is a specification.

The object of my invention is the provision of spring or flexible supports for the back bows of a vehicle-top, which supports shall be adapted to be attached to the top brace-bolts located upon the rear portion of the seat or upon the rail attached to said seat. As is well known, when the top of a vehicle is lowered 10 each back bow rests upon the top brace-bolt and supports the weight of the top, and unless some flexible means is provided for supporting the top the back bow is liable to become broken or bent or the pivotal points injured 15 by constant vibration and finally become disconnected.

My invention consists in certains novelties of construction and combinations of parts hereinafter set forth and claimed.

25 The accompanying drawings illustrate an example of the physical embodiment of my invention constructed according to the best mode I have so far devised for the practical application of the principle.

30 Figure 1 is a perspective view of a vehicle-top, showing the application of my spring-support to the top brace-bolt. Fig. 2 is a side view of the spring-support. Fig. 3 is a top plan view of Fig. 2. Fig. 4 is a view in elevation of the spring-support attached to the top brace-bolt. Fig. 5 is a partial sectional view 35 of Fig. 4. Fig. 6 is a section of Fig. 3, taken through the pad.

Referring to the several figures, the letter A 40 designates the top as a whole; B, the top bows, which are of usual construction; C, the back bows; D, the top brace or prop provided with the usual knuckle-joint; E, the seat-rail, which may be detachably or permanently secured 45 to the seat; F, the top brace-bolt, square in cross-section and to which the top brace is pivoted; G, the cap-nut; H, the spring-arms of the support; I, the coiled ends of the spring

upset or fashioned to a shape square in cross-section and which are adapted to frictionally 50 fit upon the top brace-bolt in such a manner that the coils cannot turn thereupon; J, a loop formed by reversely bending the rear portion of the spring-arms; K, a pad, preferably made of two thicknesses of leather or 55 other material stitched together at their edges; L, a slot made in the lower thickness of the leather or other material, through which may be inserted the loop J to a position between the two thicknesses of leather, and M is a 60 rivet which is passed through both thicknesses of the leather adjacent the inner portion of the loop and which holds the loop in position between the two thicknesses of leather.

The method of assembling the parts is obvi- 65 ous from an inspection of the figures of the drawings and need not be set forth.

In use when the vehicle-top is lowered the braces C rest upon the pads of the spring-supports at each corner of the seat and are 70 supported in such a manner that the springs yieldingly carry the top.

From the foregoing description taken in connection with the drawings it is clear that I have produced a spring-support which ful- 75 fils all the conditions set forth as the object and purpose of my invention.

What I claim as new, and desire to secure by Letters Patent, is—

1. The combination with a top brace-bolt 80 which is angular in cross-section, of a spring-support consisting of a bent wire having arms H, H, the free ends of which are coiled and upset or formed to fit the angular top brace-bolt, and the rear ends of the arms provided 85 with a pad.

2. A spring-support for the rear bows of vehicle-tops consisting of a wire bent upon itself to form parallel arms H, H, the free ends of which are coiled to fit an angular top brace-bolt, the rear end of the said wire being re- 90 versely bent to form a support, and a pad se- cured to the support.

3. A spring-support for the rear or back bows of vehicle-tops, consisting of a wire bent 95 upon itself to form parallel arms H, H; coiled

ends I, I; loop J; pad K having a slot L; and rivet M, securing the pad in position.

4. A spring-support for the rear bows of vehicle-tops consisting of an integral wire, bent upon itself to form parallel arms H, H; the free ends of the wire coiled and adapted to embrace a top brace-bolt; the rear portion of the wire bent to form a loop, and a pad hav-

ing a slot within which the loop is inserted and secured by suitable means.

In testimony whereof I affix my signature in presence of two witnesses.

EDWARD GALE MARTIN.
